UNITED STATES PATENT OFFICE

JOSEPH COLDWELL, OF FALL RIVER, MASSACHUSETTS

LOOM SHUTTLE

Application filed February 24, 1931. Serial No. 517,794.

This invention relates to loom shuttles for weaving and is intended to provide a reliable and satisfactory construction of shuttle that will permit the delivery of the filling 5 yarn unwound from the bobbin through an outlet eye located on one side of the shuttle near the middle portion thereof.

The shuttles most commonly in use are constructed to deliver the yarn through an outlet passage or eye located in the forepart of the shuttle, but this necessarily results in a very unequal tension of the yarn on the forward and return picks of the shuttle, because in one case the yarn draws off very 10 near the end of the shuttle and in the other case the yarn drags along nearly the whole length of the shuttle as the shuttle travels through the warp shed. It has been proposed to carry the filling yarn back from 15 the yarn passage in the forepart of the shuttle, inside the bobbin-receiving chamber of the shuttle and then carried out through an eye somewhat back of the forward end 20 of the bobbin, but in practice much difficulty is caused by the tendency of the filling 25 yarn as it unwinds from the bobbin whipping into the return stretch of yarn and by the resulting entanglement causing a 30 breakage of the yarn.

The present invention provides a construction by which the yarn may be delivered out of the shuttle through an outlet passage in the middle portion of the shuttle body, while by the use of my improved construction 35 the two stretches of yarn passing in opposite directions through the forward portion of the bobbin chamber are prevented from whipping in together and causing breakage.

Generally speaking, the invention comprises a shuttle body provided with the usual bobbin-containing chamber from which the yarn passes forward through a passage in the forepart and is then returned into the 40 bobbin-containing chamber, which is provided with a protector or guard in the form, as here shown, of a rearwardly extending partition interposed between the axis of the bobbin and the side wall of the shuttle body, said partition being arranged to pro-

tect the return stretch of the yarn passing to the outlet eye in the side wall of the shuttle against contact with the forwardly travelling yarn that whips about the bobbin as it uncoils therefrom.

In the accompanying drawing I have illustrated two forms embodying the principles of this invention applied to shuttles of slightly different type.

In the drawing

Fig. 1 is a plan view of a loom shuttle in which the protector or guard, for separating the forwardly advancing and the returning stretches of the filling yarn being delivered, is formed integrally with the 55 bobbin body itself.

Fig. 2 is a detail in side elevation of the forepart of the shuttle showing the tensioning wires for maintaining tension on the 60 yarn.

Fig. 3 is a side elevation showing the outlet side of the shuttle, the shuttle being inverted to expose that side to view.

Fig. 4 is a horizontal section on the plane X—X of Fig. 2.

Fig. 5 is a transverse section through the plane of the outlet eye on plane Y—Y of Fig. 4.

Fig. 6 is a longitudinal vertical section on plane O—O of Fig. 4.

Fig. 7 is a plan view, partly in horizontal section, showing a modified construction of my improved shuttle.

In the practice of this invention as illustrated in the drawing, the shuttle body 1 is 85 formed with the usual bobbin-containing chamber between the forepart 2 and the rear part 3, in which is mounted the bobbin-carrying spindle 4 and the filling bobbin 5 on which the filling yarn is wound for delivery in the process of weaving.

The free end of the yarn is threaded through a passage 6 in the forepart at the forward end of the bobbin chamber, thence is threaded through suitable tensioning devices, such as the coil member 7 and the vertical wires 8, a well known form of tensioning device used in weaving silk and rayon, and is then threaded back into the bobbin chamber through the passage 9, which is 95 100

bored through this part of the bobbin wall and is provided with a guide eye 10 of porcelain, or the like, to eliminate wear.

There is also provided for convenience 5 a small vertical bore 11 through which a fine hook may be inserted to draw up the forward or in-threaded portion of the yarn, so that it may be threaded into the return passage 12 which is formed by cutting a narrow kerf from the vertical bore 11 substantially parallel with the outside of the shuttle leaving a partition member 13 integral with the shuttle that acts to separate the return stretch of yarn from the forwardly moving 15 uncoiling portion of the yarn.

When the free end of the filling yarn has been threaded into the return passage 12 by whatever means, it is then threaded outwardly through the lateral delivery eye 14, 20 through which the yarn passes as it is paid out in the weaving operation. This delivery eye 14 is located in the middle area or portion of the shuttle, although not necessarily at the exact middle point.

25 As shown in Fig. 1 and in Fig. 6 of the drawing, at 13a, the top edge of the partition 13 is sloped downwardly and rearwardly so as to afford no corner or angle against which the whipping yarn can catch. It 30 therefore functions as a complete protector for preventing the entanglement of the unwinding yarn with the return stretch of the yarn as the latter passes to the outlet or delivery eye.

35 In Fig. 7 I have shown a modified construction applied to a well known type of shuttle, whose forepart 20 is provided with a threading slot 21 and a wire keeper 22, so that it is unnecessary to use a hook in 40 threading the shuttle as was the case in the form of shuttle shown in Fig. 1. In this case the yarn is passed rearwardly and through the return inlet 23 into the bobbin chamber of the shuttle and thence through 45 the outlet or delivery eye 24, whence it is supplied to the fabric in the process of weaving as the shuttle travels to and fro. In this case, instead of forming the separator or protector member integrally with the 50 body of the shuttle, as in the form first described, I cut a narrow slot or kerf in the forepart of the shuttle and insert therein a sheet 25 of light material, such as aluminum, which is fastened in place and extends 55 rearwardly in substantial parallelism with the side wall of the bobbin chamber to the neighborhood of the delivery eye 24. This is sloped downwardly at 25a toward its rear end so as to avoid forming any angle or 60 projection against which the whipping yarn could catch.

What I claim is:

1. A loom shuttle embracing in its construction, a shuttle body provided with a bobbin-receiving chamber intermediate its 65

forepart and rear part, the forepart being provided with a passage way for the yarn as it unwinds from the bobbin in said chamber, the shuttle body also being provided with a return passage for carrying the yarn 70 from the forepart to the interior of said bobbin chamber, the lateral wall of said bobbin chamber being provided with an outlet opening to receive the yarn from said return passage, and means interposed between the forwardly moving and rearwardly moving stretches of yarn preventing said stretches of yarn from being entangled with each other.

2. A loom shuttle embracing in its construction, a shuttle body provided intermediate its rear and its foreparts with a bobbin-receiving chamber, whose side wall is provided intermediate of its ends with a yarn delivering outlet, and means projecting rearwardly from the forepart and integral therewith and longitudinally spaced from said lateral wall of the bobbin-receiving chamber to allow the yarn to move rearwardly to said lateral eye without contact 90 with the stretch of yarn uncoiling from the bobbin.

3. A loom shuttle embracing in its construction, a shuttle body provided with a bobbin-receiving chamber intermediate of 95 its rear part and its forepart, one side wall of said chamber being provided with a yarn delivering outlet, that portion of the shuttle body alongside the forward portion of said chamber being vertically slotted to form a 100 return passage for the yarn to said outlet whereby the return stretch of yarn passing to said outlet from the forepart is guarded against entanglement with the stretch of yarn uncoiling from the bobbin.

4. A loom shuttle embracing in its construction, a shuttle body provided with a bobbin-receiving chamber intermediate of its rear part and its forepart, one lateral wall of said chamber being provided intermediate of its ends with an outlet for the 110 yarn, a yarn protecting member extending rearwardly from the forepart in longitudinally spaced relation to the said lateral wall, said member having its top downwardly inclined toward its rear end to prevent 115 catching of the uncoiling stretch of yarn in its whipping movement as it passes toward the forepart.

5. A loom shuttle embracing in its construction, a shuttle body provided with a bobbin-containing chamber intermediate of its rear part and its forepart, a rearwardly extending partition secured to said forepart and arranged in longitudinally spaced relation to the front portion of the side wall of said chamber, said side wall being provided with a yarn outlet adjacent the rear end of said partition, the forepart being provided with a yarn passage including yarn tension- 120 125 130

ing means and being provided with a yarn guiding passage for guiding said yarn into the space formed between said partition and the adjacent side wall.

5 In witness whereof, I have subscribed the above specification.

JOSEPH COLDWELL.
